UNITED STATES PATENT OFFICE.

FELIPE SALDANA, OF PARIS, FRANCE.

LOUD-SPEAKER.

Application filed December 8, 1926, Serial No. 153,389, and in France December 17, 1925.

The object of this invention is a loud speaker for wireless telephony, and the invention is specially concerned with the construction of the vibrating parts and of the resonant 5 diaphragm, its purpose being to suppress the nasal effect, obviate distortion, and generally to perfect the sound reproduction.

The invention relates to loud speakers of the "acoustic diaphragm" type, that is to say 10 instruments which have no cover, but have their armature fastened to a reed secured in the casing of the instrument and to a diaphragm which suitably amplifies the sound. It is a defect of existing instruments of this 15 kind that the reed and the diaphragm have well marked natural frequencies of vibration dependent on their shape and dimensions, and these natural vibrations are superposed on the forced vibrations imposed by the electromagnet on its armature, with the result 20 that listeners hear sounds which are resultant of all the vibrations, and which are a distortion of the sound intended to be reproduced. The present invention eliminates this 25 defect by preventing or reducing to a minimum the natural vibrations of the reed and diaphragm.

In essence the invention consists in subdividing the vibrating reed into several branches 30 having different natural frequencies, so that the vibrations of the reed as a whole are neutralized.

A further feature of the invention is the adoption of two diaphragms in lieu of one; 35 they may be of conical form with their apices towards one another, and must have different natural frequencies.

Other features of the invention will appear from the detailed description hereinafter.

40 The drawings show by way of example a construction of loud speaker embodying the invention;

Figures 1 and 2 are axial sections on planes at right angles of the electromagnet, vibrating reed, and armature;

45 Figure 3 is a perspective view of one construction of asynchronous reed upon a larger scale;

Figure 4 shows the construction of double 50 diaphragm above referred to;

Figures 5 and 6 are a transverse section and perspective view respectively illustrating a mounting of the instrument which makes for amplification of the sound.

55 In the construction illustrated the vibrating reed is made up of three branches. The

centre part 1 is the armature of the electromagnet 2. From it proceed three branches 3, 4 and 5. It may be seen from Figure 3 that the branch 3 is thinner than the branches 4 60 and 5, and that the branch 4 is of less width than the branch 5. Consequently the natural frequencies of the three branches are all different, and the composite reed is asynchronous, that is to say it has no natural frequency 65 of vibration, or at least its natural vibrations are instantly damped out.

It is obvious the branches may be differently arranged, or may be more in number. For instance the armature 1 might be the centre 70 of the four arms of a cross. Moreover by dividing a plate by radial slits, and making its several parts of different thickness any desired number of branches may be formed each secured to the casing at the end remote from 75 the armature. The invention is not limited to a particular number or particular arrangement of branches resulting in an asynchronous reed.

Figure 4 shows the construction of the 80 asynchronous diaphragm. The stem 6 of the reed armature is attached to two diaphragms 7, 8, which are approximately of conical form with their apices in opposition. The cones are truncated and closed by plates 10 85 which are fastened to the stem 6 by nuts 9. The diaphragms are tensioned in frames 11, 12 of suitable form, and are designed to have different natural frequencies of vibration. This arrangement besides being asynchronous, 90 enables greater tension to be put on the diaphragms without increasing the pull on the armature, since the pull exerted by the one diaphragm is opposed by that of the other. This balancing also helps the reproduction, 95 and the fact that there are two diaphragms means that there is double the vibrating surface for a given space occupied.

The material of which the diaphragms are made has a considerable effect upon the 100 reproduction. Paper, card, and varnished fabrics do not give altogether satisfactory results.

I have found that better results are obtained from celluloid or similar products 105 based on acetate and nitrate of cellulose. Very good results may be obtained from paper or fabric coated with celluloid. The celluloid is moulded hot into a form such as is shown in Figure 4. This shape is approximately that which is obtained by taking a thin sheet of a plastic and elastic material 110

such as rubber of about 0.08 to 0.15 m/m., fixing it on the periphery of a washer such as 10 and stretching it by fixing it on the periphery of a frame 11 so that the diaphragm 5 will have substantially an hyperboloidous shape. The shape of the frame 11 is preferably square, or oval. I have found that a circular shape would be less efficient and reliable. It is preferable that the thickness of the dia- 10 phragm should diminish progressively from the periphery towards the centre, and this is only possible with celluloid or other plastic material, not with paper or fabric.

I have also found it preferable that each 15 of the two diaphragms should be composed of more than one material; for instance they may have a zone of thin wood next the periphery extended to the centre by a thin sheet of celluloid.

20 The diaphragms may be made more sonorous by embodying in the celluloid by any suitable process finely divided metal such as a metal powder, on the whole surface or only on a part of that surface.

25 I have found that the construction of the diaphragms or of a diaphragm with variations in the thickness, with various materials, or with certain parts only metallized are very suitable in order to obtain aperiodic dia- 30 phragms.

It will be obvious that these features, namely the materials described, the varying thickness of diaphragm, and the zones of different composition, may be adopted in existing instruments having but a single diaphragm, and such applications are to be considered within the ambit of this invention.

The reproduction of sound by the instrument may be still further improved and 40 amplified by mounting it in the manner shown in Figures 5 and 6.

As may be seen from these figures the complete instrument comprises a frame of wood 13, within which is fixed by dowels or other 45 suitable means a sounding board 14. The casing 15 of the telephone receiver is secured in the board 14. This board may be of any suitable material, for instance of thin hard wood. The effect of this mounting is that the 50 sounding board 14 shares the vibrations of the loud speaker and improves its tone. The tone may be modified at will by suitable design of the thickness and other dimensions of the sounding board.

55 Improved means are provided for varying in simple fashion the distance of the electromagnet from its armature. These are shown in Figures 1 and 2. The electromagnet system as a whole is fastened on a plate 16 to 60 which is attached a stem 7. This stem can slide in a long sleeve 18 which extends from the casing 15. The stem is threaded at its end at 20 to receive a nut 21 which bears upon the end 22 of the sleeve 18. A spring 23 presses 65 the electromagnet 2 towards its armature 1,

and by turning the nut 21 the electromagnet may be allowed to approach the armature or may be withdrawn from it. The movement is always precisely axial by reason of the length of the stem 17 and sleeve 18.

70 It will be understood that this means of guiding, and the means of mounting in a sounding board, although particularly applicable to loud speakers, may also be applied with advantage to any similar instrument, 75 and such applications are to be considered within the scope of the invention.

What I claim is:—

1. An asynchronous vibrating armature for 80 loud speakers comprising, in combination, a rectilinear magnetic body, a pair of parallel arms on said body of different widths and a third arm on said body portion in alignment with said first mentioned arms, said third arm having a thickness less than said first mentioned arms.

2. An asynchronous vibrating armature for 90 loud speakers comprising, in combination, a rectilinear magnetic body, a pair of integral arms on said body of different widths and a third arm integral with said body in alignment with said first mentioned arms, said third arm having a thickness less than said first mentioned arms.

95 3. An asynchronous vibrating armature for loud speakers comprising, in combination, a rectilinear magnetic body, a pair of arms of equal widths and different thickness extending from said body, said arms being disposed in alignment, a longitudinally nonsymmetri- 100 cally disposed slot formed in the thicker of said arms and holes formed in said arms adjacent their extremities for receiving fastening screws.

105 4. An asynchronous vibrating armature for loud speakers comprising, in combination, a rectilinear magnetic body, a pair of arms of equal widths and different thickness extending from said body, said arms being disposed in alignment and a longitudinally nonsymmetri- 110 cally disposed slot formed in the thicker of said arms.

115 5. An asynchronous vibrating armature for loud speakers comprising in combination, a rectilinear magnetic body, a pair of arms of equal widths and different thickness integral with said body, said arms being disposed in alignment, a longitudinally nonsymmetri- 120 cally disposed slot formed in the thicker of said arms and holes formed in said arms adjacent their extremities for receiving fastening screws.

125 6. An asynchronous vibrating armature for loud speakers comprising, in combination, a rectilinear magnetic body, a pair of arms of equal widths and different thickness integral with said body, said arms being disposed in alignment and a longitudinally nonsymmetri- 130 cally disposed slot formed in the thicker of said arms.

7. An asynchronous vibrating armature for loud speakers comprising, in combination, a rectilinear magnetic body, a pair of parallel arms on said body of different widths, a third arm on said body portion in alignment with said first mentioned arms, said third arm having a thickness less than said first mentioned arms and means adapted to transmit the vibrations of said body to the vibrating membrane of the said loud speaker, disposed centrally on said body.
8. An asynchronous vibrating armature for loud speakers comprising, in combination, a rectilinear magnetic body, a pair of integral arms on said body of different widths, a third arm integral with said body in alignment with said first mentioned arms, said third arm having a thickness less than said first mentioned arms and means adapted to transmit the vibrations of said body to the vibrating membrane of said loud speaker, disposed centrally on said body.
9. An asynchronous vibrating armature for loud speakers comprising, in combination, a rectilinear magnetic body, a pair of arms of equal widths and different thickness extending from said body, said arms being disposed in alignment, a longitudinally nonsymmetrically disposed slot formed in the thicker of said arms and means adapted to transmit the vibrations of said body to the vibrating membrane of said loud speaker, disposed centrally on said body.
10. An asynchronous vibrating armature for loud speakers comprising, in combination, a rectilinear magnetic body, a pair of arms of equal widths and different thickness extending from said body, said arms being disposed in alignment, a longitudinally nonsymmetrically disposed slot formed in the thicker of said arms, holes formed in said arms adjacent their extremities for receiving fastening screws and means adapted to transmit the vibrations of said body to the vibrating membrane of said loud speaker, disposed centrally on said body.
11. An asynchronous vibrating armature for loud speakers comprising in combination, a rectilinear magnetic body, a pair of arms of equal widths and different thickness integral with said body, said arms being disposed in alignment, a longitudinally nonsymmetrically disposed slot formed in the thicker of said arms, holes formed in said arms adjacent their extremities for receiving fastening screws and means adapted to transmit the vibrations of said body to the vibrating membrane of said loud speaker, disposed centrally on said body.
12. An asynchronous vibrating armature for loud speakers comprising, in combination, a rectilinear magnetic body, a pair of arms of equal widths and different thickness integral with said body, said arms being disposed in alignment, a longitudinally nonsymmetrically disposed slot formed in the thicker of said arms and means adapted to transmit the vibrations of said body to the vibrating membrane of said loud speaker, disposed centrally on said body.

In testimony whereof I have signed my name to this specification.

FELIPE SALDANA.
